[57] CLAIM

The ornamental design for a cigarette case, as shown and described.

DESCRIPTION

FIG. 1 is a perspective view of a cigarette case, showing my new design and shown open;

FIG. 2 is a perspective view of the cigarette case as it appears when closed;

FIG. 3 is a rear elevational view thereof;

FIG. 4 is a side elevational view, the opposite side being a mirror image thereof;

FIG. 5 is a bottom plan view thereof.

The broken line disclosure of a pack of cigarettes in FIG. 1 is for illustrative purposes only and forms no part of the claimed design.

FIG. 1

FIG. 3

FIG. 5
